TOOL FOR GRINDING CONICAL BEARINGS

George W. Holcomb, East Rochester, N. Y.

Application November 13, 1935, Serial No. 49,525

10 Claims. (Cl. 51—236)

This invention relates to watch makers' tools and has for its object to provide a hand tool by means of which conical center bearings may be accurately ground on the end of pivot pins such as balance staffs etc.

Another object of this invention is to so construct the tool that it may be adjusted to a wide range of sizes of balance staffs and balance wheels for regrinding the conical ends of the balance 10 staffs.

A further object of this invention is to construct the tool so as to provide an absolutely free and axially true rotation of the staff during the grinding operation.

15 All these and other objects of this invention and attendant advantages will become more clearly apparent from the detailed description of it which follows, reference being had to the accompanying drawing in which

20 Figure 1 is a top plan view of the tool.

Figure 2 is a front elevation thereof.

Figure 3 is a side elevation of the tool with a balance wheel and staff mounted therein and held against a grinding wheel to have the conical bearing of the staff accurately reground thereon.

Figure 4 is an enlarged vertical sectional view of the upper portion of the tool with a balance wheel and staff mounted thereon, the section of the tool being taken on the line 4x—4x of Figure 3.

30 Figure 5 is a top plan view of the enlarged tool illustrated in Figure 4.

Figure 6 is a horizontal section of the enlarged tool taken on the line 6x—6x of Figure 4.

In the several figures of the drawing like reference numerals indicate like parts.

The hand tool forming the subject matter of my present invention is especially adapted for use in accurately regrinding or refinishing the conical bearing ends of balance staffs carrying the balance wheel of watches, clocks etc. and the novel construction of the tool makes it possible to perform this operation with precision and without the aid of a machine tool such as a lathe.

45 As illustrated in the several figures of the drawing the tool comprises a substantially rectangular frame 1 which is split at one end in the middle thereof to provide a pair of opposing jaws 2 and 3 at the end of the frame. The frame 1 is preferably formed up of spring metal stock so as to make the sides thereof yieldable and normally cause the jaws 2 and 3 to be yieldingly held against each other. The jaws are suitably tapered toward their ends as illustrated in Figures 1 and 5

55 and in the edge of each of the jaws is provided a triangular recess 6 so that the recesses of both of the jaws together form a substantially rhombically shaped opening between them.

60 The closed end 4 of the frame 1 is provided with a hole 5 thru which projects the hollow stem 7

to have the frame 1 rest on the shoulder 8 thereof and be clamped thereto by means of the lock nut 9. The frame is thus fixed on the hollow stem which is threaded on the inside to have the supporting stem 10 threaded therethru and provide an adjustable extension thereof. The outer end of this supporting stem is suitably mounted in a hollow handle 11 so that the stem may be rotated by means of this handle and suitably adjusted in the frame 1.

10 For the purpose of locking the supporting stem 10 after it has been adjusted in the frame 1, the hollow stem 7 is threaded on the outside of the frame and is provided with a tapered end which is split to make it contractible so that the outer 15 opening in the locknut 12 threaded on the hollow stem can engage and contract the end of the hollow stem and grip the supporting stem to keep it from rotating therein.

The sides of the frame 1 are spread to move the 20 jaws 2 and 3 by means of the spreading member 13. This member comprises a preferably flexible cross bar which is bifurcated at the ends to engage the inside and the edges of the frame to keep it in engagement therebetween. In the 25 middle of the cross bar is provided a hole 14 thru which projects the hollow stem 7 with the adjusting nut 15 threaded thereon to have this nut movable against the spreading member and force this member down the inwardly curved 30 lower ends of the sides of the frame to cause these sides to spread.

The handle 11 is preferably made hollow and within it may be mounted a removable screw 35 driver or other suitable tool.

The tool is used as follows:

The balance wheel is inserted into the frame 1 by forcing one end of the balance staff thru the rhombically shaped opening provided between the jaws 2 and 3 thereof to cause these jaws to spread and yieldingly grip the staff and hold it centered between the triangular recesses therein. With the staff held between the jaws, the opposite end of the staff is centered in the female conical bearing 17 provided in the end of the supporting stem 10 so as to place the staff in perfect axial alignment with the supporting stem. The supporting stem is then adjusted in the frame to move the staff to a position in which the free end of the staff projects a suitable distance from the frame to permit the conical bearing thereof to be conveniently held against the surface of a grinding wheel. With the staff and balance wheel in this position, the supporting stem is locked in the hollow stem 7 to prevent a further movement thereof and provide a fixed center bearing for the staff in the end of the supporting stem.

The jaws 2 and 3 retain their grip on the balance staff during the endwise adjustment thereof and thus prevent the disengagement of 60

the staff from the center bearing in the supporting stem except when this stem is deliberately moved away from it to permit the staff to be moved into the frame for adjustment purposes.

5 For the grinding operation the staff with the balance wheel is then released from the pressure of the jaws to permit the staff to freely rotate between them in an axially true rotation. This is done by moving the adjusting nut 15 against 10 the spreading member 13 to cause this member to gradually force the sides of the frame outwardly until the jaws 2 and 3 thereof retain but a very slight frictional engagement with the staff by means of the edges of their triangular recesses.

15 In this way the staff is kept centered in the recesses and the friction of the jaws removed from it to allow the staff to freely rotate between the jaws while being held to a true axial rotation by its engagement with the center bearing in the 20 end of the supporting stem 10.

The staff is then ready for grinding which is done by holding the tool so as to present the free conical bearing end of the staff at the proper angle to the grinding surface of the wheel and 25 cause the frictional contact of the grinding surface to rotate the staff during the grinding operation in order to produce an accurately centered conical bearing on the staff. The process is repeated for the conical bearing at the opposite end of the staff to refinish both bearings and make them rotate axially true when mounted in their bearings.

I claim:

1. A tool for grinding conical bearings on balance staffs and other pivot pins comprising a supporting stem, a female center bearing in the end of said stem adapted to have one end of the balance staff centered therein, a holding frame surrounding said stem, recessed spring jaws carried 40 by said frame to form a friction bearing above said conical bearing to yieldingly embrace the balance staff supported in the center bearing and hold it in line with said stem, and means for releasing the yielding pressure of said spring jaws on the balance staff to permit a free and axially 45 true rotation of the staff between the spring jaws and the center bearing.

2. A tool for grinding conical bearings on balance staffs and other pivot pins comprising a holding frame, a stem movable endwise in said frame, a female center bearing in the end of said stem within said frame to pivotally support the end of a balance staff therein, recessed spring jaws carried by said frame to form a friction bearing above said center bearing to yieldingly embrace the balance staff and hold it in the center bearing in line with said stem and means for spreading said jaws to release the pressure of the jaws on the balance staff and permit a free and axially true rotation of the staff between said jaws and the end of said stem.

3. A tool for grinding conical bearings on balance staffs and other pivot pins comprising a spring frame, recessed gripping jaws provided 65 on said frame, a stem threaded in one end of said frame so as to be movable toward and away from said gripping jaws, a female center bearing in the end of said stem within said spring frame, a spreading member movable on said stem within 70 said frame to spread said frame and gradually separate said jaws.

4. A tool for grinding conical bearings of balance staffs and other pivot pins comprising a spring frame, a pair of recessed jaws provided

at one end of said frame normally engaging each other to provide an expandable bearing between them, a threaded sleeve in the opposite end of said frame and projecting inwardly and outwardly thereof, a supporting stem threaded thru 5 said sleeve to move endwise therein, a female center bearing in the end of said supporting stem within said frame and a handle on said stem on the outside of said frame and means movable on said sleeve and engaging said frame to move said jaws and cause said expandable bearing to increase or decrease in size.

5. A tool as set forth in claim 4 including means for contracting said sleeve to adjustably lock said threaded stem into said sleeve. 15

6. A tool for grinding conical bearings of balance staffs and other pivot pins comprising a frame having normally substantially parallel and yielding sides, jaws at the free ends of said sides normally abutting each other with triangular recesses in each of said jaws forming a substantially rhombically shaped opening between them, a supporting bearing within said frame to pivotally support a balance staff within the frame with the staff clamped between the recesses in 25 said jaws and means for expanding the sides of said frame to spread said jaws to release their pressure on the balance staff until freely and axially rotatable in said triangular recesses with the staff pivotally supported at one end in said 30 supporting bearing and projecting from said frame with the other end.

7. A tool for grinding conical bearings of balance staffs and other pivot pins as set forth in claim 6 in which said jaws taper toward the triangular recesses therein to reduce their gripping surfaces to substantially the width of the recesses.

8. A tool for grinding conical bearings of balance staffs and other pivot pins comprising a 40 threaded contractible sleeve, a supporting stem threaded thru said sleeve, a clamping nut threaded on the outside of said sleeve to contract it and lock said supporting stem against movement in said sleeve, a substantially rectangular 45 and split frame supported on said sleeve with one end thereof, a lock nut threaded on said sleeve and engaging said frame to hold said frame on said sleeve, a spreading member extending across said frame on the inside thereof with said sleeve 50 projecting thru the spreading member, a nut threaded on said sleeve and engaging said spreading member to cause said spreading member to spread the sides of said frame and open the frame. 55

9. A tool for grinding conical bearings of balance staffs and other pivot pins as set forth in claim 8 in which the split end of the frame is provided with oppositely located triangular recesses so as to have the opening provided thereby 60 axially in line with said supporting stem and a female center bearing in the end of said stem to support the end of a balance staff on said supporting stem and have the staff project thru the opening provided by said triangular recesses 65 between the split end of the frame.

10. A tool as set forth in claim 8 in which the spreading member is bifurcated at the ends to embrace the sides of the frame and hold the spreading member in engagement with the frame 70 and cause the frame to guide the spreading member in its movement.

GEORGE W. HOLCOMB.
